UNITED STATES PATENT OFFICE.

HOWARD L. KENNEDY, OF FORT WAYNE, INDIANA.

DESIGN FOR A TRAVELER'S GRIP OR BAG.

46,312.

Specification for Design.

Patented Aug. 25, 1914.

Application filed June 8, 1914. Serial No. 843,891. Term of patent 14 years.

To all whom it may concern:

Be it known that I, HOWARD L. KENNEDY, a citizen of the United States, residing at Fort Wayne, in the county of Allen and State of Indiana, have invented a new, original, and ornamental Design for a Traveler's Grip or Bag, of which the following is a full, clear, and exact description, reference being had to the accompanying drawing, forming a part hereof.

My invention relates to a design for a traveler's bag or grip that is very attractive and pleasing in appearance.

In the drawings: the drawing represents a perspective view of said grip.

Referring to the drawings, it will be seen that this grip has a shape conforming sub-

stantially to that of a common rectangular shed with a pitch roof with inclined sides of practically an angle of forty-five (45) degrees, and with the ridge flattened. This grip is provided at its lower angles with suitable corner fixtures, and its ends are paneled.

I claim—

The ornamental design for a grip, as shown and described.

In witness whereof, I have hereunto set my hand this 21st day of May, 1914.

HOWARD L. KENNEDY.
